TEAKETTLE

Manuel S. Ziskin, University Heights, and Ralph B. Billig, Erieside, Ohio, assignors to Kromex Corporation, Cleveland, Ohio, a corporation of Ohio

Application February 1, 1949, Serial No. 602

Term of patent 14 years

(Cl. D44—25)

To all whom it may concern:

Be it known that we, Manuel S. Ziskin and Ralph B. Billig, citizens of the United States, residing at University Heights, county of Cuyahoga, and State of Ohio, and Erieside, county of Lake, and State of Ohio, respectively, have invented a new, original, and ornamental Design for a Teakettle, of which the following is a specification, reference being had to the accompanying drawing, forming a part hereof:

Fig. 1 is a top plan view of a teakettle, showing our new design; and

Fig. 2 is a side elevational view thereof.

We claim:

The ornamental design for a teakettle, substantially as shown.

MANUEL S. ZISKIN.
RALPH B. BILLIG.
